UNITED STATES PATENT OFFICE.

JOHN JOHNSON, OF DULUTH, MINNESOTA.

GRAIN-CAR DOOR.

No. 844,024.

Specification of Letters Patent.

Patented Feb. 12, 1907.

Application filed March 10, 1906. Serial No. 305,236.

To all whom it may concern:

Be it known that I, JOHN JOHNSON, a citizen of United States, residing at Duluth, in the county of St. Louis and State of Minnesota, have invented certain new and useful Improvements in Grain-Car Doors, of which the following is a specification.

My invention relates to improvements in grain-car doors, and has for its objects the provision of a door which will allow of the ready loading and unloading of the car, which will form a perfectly-tight closure and prevent loss of the grain, and which will allow the removal of the grain either in bulk or in limited amounts.

Other objects of the invention are the provision of a device of the character stated which can be quickly stored out of the way when it is desired to load the car with heavy articles and also to provide a door which will not become jammed and stick from the pressure of the grain.

My invention further has for its object to provide a grain-car door of simple and durable construction, light and easily manipulated, and practical for the purposes intended.

With these and other objects in view my invention consists of a car-door comprising an upper door-section having a swinging and vertically-sliding movement, a lower door-section slidably engaged in the upper door-section and adapted to engage grooves in the door-posts, means for elevating the door-sections, and a supplemental door-section hinged to the upper portion of the door-frame.

My invention further consists of a car-door embodying certain other novel features of construction, combination, and arrangement of parts, substantially as herein disclosed.

Figure 1 is a side elevation of a portion of a car with my improved door in place thereon. Fig. 2 is a vertical sectional view through the door and a portion of the car. Fig. 3 is an elevation of the door, taken from the interior of the car; and Fig. 4, a vertical sectional view through the car, showing the door as stored when not in use.

In the drawings, the numeral 1 designates the door-posts of the car, to the lower inner sides of which are secured the guiding-strips 2, which provide grooves 3 for the reception of the lower door-section 4. This door is preferably of sheet-iron, and brackets 5 are secured near the upper corners thereof, in which are mounted the pulleys 6. Comple-

mentary pulleys 7 are mounted in brackets 8, secured to the upper portion of the door-frame. These brackets 8 are provided with lower extensions 9, in which are secured the hoisting ropes or cables 10, which pass over the pulleys and are adapted to hang down over the outside of the door-section. The upper door 11 may be of iron, as is the other door-section, and is formed with the inturned edges 12, providing guideways for the reception of the lower door-section.

To provide for the ready inspection of the grain, I have shown this upper door-section provided at its upper portion with the removable boards or panels 13, secured thereto by the brackets 14. At the upper corners of this door-section lugs are secured, which provide the horizontal pintles 15, adapted to be engaged by the guide-rods 16, secured to the door-posts. At the upper ends these rods are so bent as to form the retaining-loops 17. Thus it will be seen that the lower door-section may be hoisted and slide up within the flanges of the upper door-section.

An upper supplementary door-section 18 is hinged at 19 to the door-frame by means of the offset hinges 20 and is provided at its lower edge with the overlapping strip 21 to engage the upper door-section and form a close joint therewith. A sliding latch 22 is secured in brackets 23 on the outer face of the supplementary door-section and serves to lock said door to the upper door-section when so desired, or by engaging the keeper 24, secured to the car-roof, it serves to secure the door-section in the open position.

An eye 25 is provided at the lower edge of the upper door-section, in which is secured a rope or cable 26, which passes upward over the pulley 27, secured to the roof-beam 28, thence to the pulley 29, secured to the door-frame, and down.

When the car is to be loaded, the supplementary door-section is swung up out of the way and the upper and lower door-sections are closed. The car may then be filled to its full capacity, after which the supplementary door-section is closed and latched and the outside door of the car is closed and sealed.

If grain is to be removed for testing, the supplementary door-section may be opened, or, if necessary, some of the boards in the upper door-section may be removed. When ready to unload, the lower door-section is hoisted within the flanges of the upper door-section by means of the hoisting-ropes, and

the grain will run out in such volume as desired.

When the car is to be loaded with heavy goods and it is desired to store the grain-door section out of the way, the supplementary door-section is first hinged up to the roof of the car. The lower door-section is housed within the upper door-section, and the upper door-section is lifted until the 5 pintles engage the retaining-loops in the guide-rods. Then the door-sections are swung up to the roof of the car by means of the rope 26, and the rope is secured in the cleat 30, mounted on the door-post. A door-sill 31, preferably of sheet-iron, is provided, which prevents leakage of the grain under the door. A hook or cleat 32 may be mounted in the lower door-section, so that the said 10 door-section may be easily started or raised 15 by means of a crowbar or similar tool.

From this description, taken in connection with the drawings, it will be evident that I have provided a grain-door which accomplishes all the objects herein set forth and 20 which is entirely practical and efficient in 25 every particular.

I claim—

1. A grain-door comprising a door-frame, an upper door-section pivotally slidable in 30 said frame, retaining-flanges near the inner edges of said door-section, a lower door-sec-

tion slidable within said retaining-flanges, and guide-bars for the upper door-section adapted to form pivotal supports to said section.

2. In a grain-door, the combination with a frame, an upper door-section pivotally slidable in said frame, retaining-flanges near the edges on the inner side of said section, a lower door-section slidable in said flanges, 40 and a supplementary door-section hinged to the roof of the car and adapted to engage the upper door-section.

3. A grain-door comprising a door-frame, an upper door-section pivotally slidable in 45 said frame and provided with a cut-away portion along its upper edge, removable panels covering said portion, guide-bars adapted to form pivotal supports for the upper door-section, retaining-flanges on the inner face of 50 the upper section, a lower door-section slidable within said flanges, a supplementary door-section hinged to the roof of the car and adapted to engage the upper door-section, and means for locking said supplementary 55 section to the upper section or to the roof.

In testimony whereof I affix my signature in presence of two witnesses.

JOHN JOHNSON.
